UNITED STATES PATENT OFFICE.

RUDOLPH WEHR, OF LOS ANGELES, CALIFORNIA, ASSIGNOR TO THE WEHR MOTOR COMPANY, A CORPORATION OF CALIFORNIA.

VALVE CONSTRUCTION.

Application filed March 21, 1928. Serial No. 263,253.

My invention relates to improvements in valve constructions and more particularly to valves for internal combustion engines in which means are provided for automatically compensating for the temperature and wear changes to which such constructions are subjected so that any leakage may effectively be prevented, and also to compensate for any deleterious effects resulting from the explosive force in such engines.

Various devices and mechanisms have already been proposed for compensating for temperature and wear changes, such as wedges and the like, but they have fallen far short of accomplishing the objects intended, for it is a most difficult feature to successfully pack a rotary surface.

It is my main purpose, therefore, to do away with wedges entirely, and use instead a purely wedging action, rather than use a wedge, which feature, so far as I am aware, has never before been used for providing a compensating means for a rotary valve. Moreover, in modern internal combustion engine practice no means has been provided for compensating for the rapid blows to which such valves are subjected by the explosions in said engines.

To this end, it is an object of my invention to provide a novel form of valve construction in which an automatically actuated compensating device in the form of a shoe or mobile member having a curved surface positioned on the rotary valve of an internal combustion or other engine, which shoe is also preferably provided with a plane surface adapted to coact with the plane surface of an oscillating device to produce a purely wedging action on a rotary valve for compensating for temperature and wear changes to prevent leakage, and also to compensate for the explosive force in said engine on said valve.

It is also within the province of my invention to position the oscillating device off-center with respect to the vertical transverse axis of the rotary valve, the vertical center line of said device being positioned off-center or eccentric toward the direction of rotation of said valve.

The above and further objects and advantages of my invention, as will herein-after more fully appear, I attain by the apparatus constructed in accordance with the specification, and illustrated on the

drawings forming a part of my application.

Reference is had to the accompanying drawings, in which similar reference characters denote similar parts. In the drawings,

Fig. 1 is a transverse sectional view taken through the cylinder head of an internal combustion engine showing my invention applied thereto, the parts being in the position when the engine is partly warmed,

Fig. 2 is a similar view, but showing the valve in a different position, the compensating device being also shown in operative position, slightly exaggerated.

Fig. 3 is a fragmentary longitudinal sectional view, taken on the line 3—3, Fig. 1, looking in the direction of the arrows, and

Figs. 4 and 5 are diagrammatic views showing in exaggerated form the positions taken by the compensating devices with respect to the vertical transverse axes of the valve and the oscillating device.

Describing my invention more in detail, the cylinder head 2 is provided with the usual water jacket 4, which cylinder head may be associated with the cylinders 6, containing the pistons 8, in any way in practice preferred, said cylinders being provided with the usual inlet ports 10.

The valve casing 12 is shaped to house the rotary valve 14, which valve is provided with the usual cut-away portions forming respectively the inlet passages 16 and exhaust passages 18, adapted to be intermittently and in sequence connected with the inlet ports 20 and exhaust ports 22 and the cylinder inlet ports 10.

Positioned on the valve 14, and adapted to be moved circumferentially with respect thereto, is the compensating shoe or mobile member 24, which member is provided with a curved surface 26 fitting snugly over the valve 14; as seen more particularly in Figs. 1 and 2, said shoe being positioned and operable in the extension 28 of the valve casing 12, said extension having a curved or bulging portion 30 in which is positioned and operable therein the oscillating member or device 32, which device has a curved top surface and a lower plane surface 34, which plane surface is adapted to coact with the upper plane surface of the shoe 24 to produce the wedging action presently to be explained. It will of course be understood that the valve, shoe and oscillating member

or device extend the longitudinal length of the cylinders 6. See Fig. 3.

For the purpose of continually urging the shoe 24 to the valve 14, the conventional 5 spring and adjustable nut structure 36 is provided, the valve 14 being also provided with the cut-away portion 38 covering the port 10 on the compression stroke of the piston 8, a screw-threaded cavity 40 being 10 also provided for the reception of the usual spark plug.

The relation of the compensating means with respect to the valve 14 is shown dia- 15 grammatically on Figs. 4 and 5. As seen in said figures, the transverse vertical axis O of the oscillating device 32 is positioned eccentric or off-center with respect to the transverse vertical axis through the center of the valve 14, said axis O being shown to 20 the left of the axis V or toward the direction of rotation of the valve, rather than to the right, this feature being shown exaggerated for the sake of clearness.

The various parts of the compensating 25 means are in the position shown in Fig. 2 when the engine is cold or when it is fully heated, and Fig. 1 shows the parts in the position they assume when the engine has been but partly heated, the external portions 30 being still cold. When the engine is fully heated, the oscillating device 32 and the shoe 24 have moved from the position shown in Fig. 1 to that shown in Fig. 2.

Due to the excessive number of blows produced by the rapid explosions in the engine 35 cylinders, there is a continual hammering on the valve 14. So far as I am aware no structure heretofore proposed for compensating for this feature has ever been pro- 40 vided.

Due to the eccentric or off-center relation between the axes O and V, as hereinbefore described, the force of the rapid fire explosions in the cylinders are communicated to 45 the valve 14, and directly to the shoe 24, which shoe coacts with the off-center oscillating device 32 to produce the wedging action hereinbefore explained, said shoe 24 being continually urged against the periphery of said valve. This is accomplished by positioning the axis O to the left of the axis V, or toward the direction of the rotation of the valve, which rotation is indicated by the arrows. Obviously, no such action 50 could be had if the axis O were positioned to the right of the axis V.

In addition to this compensating feature, the wedging action of the parts 32 and 24 compensate for temperature and wear 55 changes in the valve 14 as explained.

The operation of the apparatus should now be clear. The temperature and wear changes and the rapid fire blows of the explosions in the cylinders cause the spring 60 36 to expand or contract, the device 32 os-

cillating freely in the curved portion 30, and its plane surface coacting with the plane surface of the shoe 24 to move said shoe circumferentially, either clockwise or counter clockwise, an effective wedging action being 70 thus produced to hold said shoe to the valve and the valve to its seat so that there can be no leakage between the inlet and exhaust ports 20 and 22. The member 32 and shoe 24 may be adjusted by the adjusting nut 75 of the spring 36 so that they may move relatively any distance desired.

While I have thus described my invention with great particularity, it will be clear that the same may be modified throughout a wide range. I accordingly do not propose to be limited to the exact details of construction described and claimed, but reserve the right in practice to make any and all changes that fall within the scope of the appended claims.

I claim as my invention:

1. In a valve construction, a valve casing, a rotary valve in said casing, said casing being provided with a curved portion, an oscillating device in said curved portion, a spring-pressed member slidable on said device as said device is oscillated, said member being adapted to coact with said device to produce a wedging action of said member on said valve.

2. In a valve construction, a valve casing, a rotary valve in said casing, said casing being provided lengthwise thereof with a curved portion, a curved member positioned in said curved portion and oscillatable therein, and a shoe adapted to coact with said member to produce a wedging action of said shoe against said valve.

3. In a valve construction, a valve casing, a rotary valve in said casing, an automatic compensating device associated with said valve, said device comprising a shoe movable circumferentially of said valve, and an oscillating device positioned off center with respect to said valve, said shoe and said oscillating device being adapted to coact to provide a wedging action of said compensating device on said valve.

4. In a valve construction, a valve casing, a rotary valve in said casing, and automatic means for compensating for the rapid fire explosions in the cylinders with which said valve is associated, said means including a shoe and an oscillating device positioned off-center or eccentric with respect to the transverse vertical axis of said valve and toward the direction of rotation of said valve.

5. In a valve construction, a housing, a rotary valve therein, and a compensating means, comprising a shoe movable circumferentially of and by said valve, and a pivot thrust for said shoe and relatively to which said shoe is movable.

6. In a valve construction, a housing, a

- rotary valve therein, and a compensating means, comprising relatively movable members, one of said members movable circumferentially of and by said valve.
- 5 7. In a valve construction, a housing, a rotary valve therein, and a compensating means, comprising an oscillatable thrust, and a valve-engaging shoe movable circumferentially of and by said valve and relatively to said thrust.
- 10

8. In a valve construction, a housing, a valve therein, and a compensating means comprising a shoe movable circumferentially of said valve, and a pivot-thrust for said shoe disposed laterally of the axis of rotation of said valve and relatively to which said shoe is movable.

In testimony whereof I have signed my name to this specification.

RUDOLPH WEHR.
